UNITED STATES PATENT OFFICE.

FRANK A. REDNER, OF MENOMINEE, MICHIGAN.

TOY BLOCK AND PROCESS OF PRODUCING THE SAME.

Application filed February 19, 1923. Serial No. 619,958.

To all whom it may concern:

Be it known that I, FRANK A. REDNER, a citizen of the United States, residing at Menominee, in the county of Menominee and

5 State of Michigan, have invented certain new and useful Improvements in Toy Blocks and Processes of Producing the Same, of which the following is a specification.

The present invention relates to toy blocks 10 and the process of producing the same and more particularly to solid blocks which are usually made of wood.

It is the object of the present invention to provide a novel method of producing blocks 15 of this character and to provide such blocks with rounded edges and corners which not only produce a better appearance, but will not break or split as easily and are not as apt to cause injury to other objects or to 20 children playing with them.

In the accompanying drawings,

Figure 1 is a perspective view of a block constructed in accordance with the present invention,

25 Figure 2 is a view in elevation of a portion of the blank,

Figure 3 is a sectional view of the completed article.

The block disclosed is designated 4, and is 30 in the form of a cube of wood or other material, the fibre or material of which can be compressed. As initially formed, and as shown in Figure 2, a blank is provided, having relatively sharp edges 5 and sharp corners 6. In forming the block, letters 7 and frames or borders 8, are produced by dies which compress the material around said letters and borders, leaving the latter raised or in anaglyphic form. The dies are also 35 formed so as to simultaneously compress the marginal portions and corners 5 and 6 into rounded formation, as indicated at 9 and 10. This not only produces said rounded edges and corners, but the material formed by the 40 angular portions 5 and 6 is forced into the body behind said rounded portions, as indicated at 11 in Figure 3, thus reenforcing

said material and producing a hardened surface that will take a good polish and will not be readily marred or disfigured by rough 50 usage.

From the foregoing, it is thought that the construction, operation and many advantages of the herein described invention will be apparent to those skilled in the art, without further description, and it will be understood that various changes in the size, shape, proportion and minor details of construction may be resorted to without departing from the spirit or sacrificing any of the 60 advantages of the invention.

Having thus fully described my invention, what I claim as new, and desire to secure by Letters Patent, is:

1. A toy block comprising a solid body of compressible material having angularly disposed faces, certain of said faces having raised symbols and a raised marginal border surrounding the symbols, the edge and corner portions of the body being located outside the border and said portions being compressed to round off the corners and edges, leaving the border inside the planes of the sides and protected by the compressed portions outside the same. 65

2. The process of producing toy blocks which consists in forming a block of compressible material having angularly disposed faces and with sharp meeting edges and corners, compressing certain of the margins of said block to compact the material and thereby round off the corners and edges, leaving a strip uncompressed at the inner sides of the compressed portion forming within the same an upstanding border, and compressing certain portions within the border to cause the latter and a predetermined design to upstand from the finished face of the block and to produce a border that is within the planes of the compressed margins 85 of the block. 90

In testimony whereof, I affix my signature.

FRANK A. REDNER.
